& Bear, LLP(57) CLAIM

The ornamental design for a redelivery notice form, as shown and described.

DESCRIPTION

FIG. 1 is a front view of a first embodiment of a redelivery notice form in accordance with the new design;

FIG. 2 is a back view thereof;

FIG. 3 is a front view of a second embodiment of a redelivery notice form in accordance with the new design;

FIG. 4 is a back view thereof;

FIG. 5 is a front view of a third embodiment of a redelivery notice form;

FIG. 6 is a back view thereof;

FIG. 7 is a front view of a fourth embodiment of a redelivery notice form; and,

FIG. 8 is a back view thereof.

The broken line showing of portions of the redelivery notice form is included for the purpose of illustrating environmental structure and form no part of the claimed design. The diagonal lines are used to indicate shading and do not depict any particular color or texture. The redelivery notice form has no appreciable thickness.
